UNITED STATES PATENT OFFICE.

AUGUST SCHOELLHORN AND HERMAN S. ALBRECHT, OF ST. LOUIS,
MISSOURI.

DRIER.

SPECIFICATION forming part of Letters Patent No. 732,451, dated June 30, 1903.

Application filed April 13, 1903. Serial No. 152,313. (No model.)

To all whom it may concern:

Be it known that we, AUGUST SCHOELLHORN and HERMAN S. ALBRECHT, citizens of the United States, residing in the city of St. Louis, in the State of Missouri, have invented certain new and useful Improvements in Driers, of which the following is a full, clear, and exact description, reference being had to the accompanying drawings, forming part of this specification.

Our invention relates to a machine more especially intended for the purpose of drying clay, but which may be used for drying other materials.

15 The object of our invention is to construct a drier which will be comparatively inexpensive to make and which will be durable and simple in its operation and which will effectually perform its work.

20 Our invention consists in features of novelty hereinafter fully described, and pointed out in the claim.

Figure I is a front view of our improved machine. Fig. II is a rear end view. Fig. 25 III is a horizontal longitudinal section, part broken away, taken on line III III, Fig. 1. Fig. IV is a vertical transverse section of the drier.

Referring to the drawings, 1 represents a cylinder located in a suitable furnace 2, by which the necessary heat for drying purposes is produced. The cylinder is provided internally with spiral flights 3, which act to turn the material over and keep it stirred up. To each end of the cylinder outside of the furnace is secured a ring or circular rail 4. Each ring rests upon a pair of grooved rollers 5, secured to short shafts 6, that are journaled in boxes 7, mounted on standards 8. The two rollers of each pair are placed sufficiently far apart to allow their ring 4 to fit down between them, as shown in Fig. I, the cylinder being thus supported in a substantial manner. The two shafts 6 on one side of the ma-

chine are provided with cog-wheels 9, that are engaged by pinions 10 on a drive-shaft 11, provided with a pulley 12. As the shaft 11 is revolved the cylinder 1 is kept turning, owing to the friction between the rings 4 and the two rollers 5, the shafts of which are 50 geared to the shaft 11.

At the front end of the cylinder the machine is provided with a feed-funnel 13, held in position by brace-arms 14, and this end of the cylinder has a head 15 with a central opening to receive the inner end of the funnel 13. At the other end of the machine the cylinder has an open end and discharges into a spout 16.

We claim as our invention—

A drier for clay, comprising a furnace, a cylinder open at each end arranged horizontally through the furnace, projecting therefrom at each end, spiral flights within the cylinder, wide rings secured to the projecting ends of the cylinder, a pair of grooved rollers for each ring, shafts supporting opposite rollers on opposite ends of the furnace, standards having journal-boxes for the shafts, spaced from the end walls of the furnace to permit the rollers to be supported upon the shafts between the furnace end walls and the standards, cog-wheels upon each end of one of the shafts, a drive-shaft parallel with the roller-shaft, pinions on the drive-shaft meshing with the cog-wheels, a funnel at one end of the furnace projecting into the open end of the cylinder, brace-arms connected with the furnace and the top of the funnel, and an inverted-U-shaped brace connected at its ends to the standards, and supporting the funnel from beneath.

AUGUST SCHOELLHORN.
HERMAN S. ALBRECHT.

In presence of—
NELIE V. ALEXANDER,
E. S. KNIGHT.
